UNITED STATES PATENT OFFICE.

WALTER F. STIMPSON, OF DETROIT, MICHIGAN, ASSIGNOR TO STIMPSON SCALE AND MANUFACTURING COMPANY, OF NORTHLAKE, MICHIGAN, A CORPORATION OF MICHIGAN.

PITLESS SCALE.

No. 903,910.

Specification of Letters Patent.

Patented Nov. 17, 1908.

Application filed December 30, 1907. Serial No. 408,586.

To all whom it may concern:

Be it known that I, WALTER F. STIMPSON, a citizen of the United States of America, residing at Detroit, in the county of Wayne 5 and State of Michigan, have invented certain new and useful Improvements in Pitless Scales, of which the following is a specification, reference being had therein to the accompanying drawings.

10 The invention relates to wagon scales of that type known as pitless, and the invention consists in certain features of construction as hereinafter set forth.

In the drawings—Figure 1 is a perspective view of the scale, with a portion of the platform removed; Fig. 2 is a perspective view of the supporting fulcrum loop for the lever; Fig. 3 is a plan view thereof; Fig. 4 is a perspective view of the shackle connection for the levers; and Fig. 5 is a section thereof.

The stationary frame of the scale comprises end sills A and B, which are cross connected with each other by rods C. These 25 rods not only form a structural part of the frame, but also are employed for supporting the hangers for the platform levers, and the arrangement is such as to greatly condense the vertical height of the space necessary for said levers.

As shown, the rods C are tubular, and are connected to the sills B by being threaded at their ends to pass through apertures in the web portions of the sill. Upon the 35 threaded portion of the rods is secured a correspondingly threaded collar D, which forms an abutment bearing against the inner face of the sill, while a clamping nut engages the outer end of the rod and bears 40 against the outer face of the sill. The collar D, in addition to forming a part of the locking device for the rods and sills, also cooperates with the platform lever hangers, as will be hereinafter described.

45 The platform levers preferably consist of a pair of main levers and a coöperating pair of short levers, the former E E extending from the outer opposite ends of the frame diagonally across the same, and having their 50 free ends suitably connected with the steel yard rod. The short levers E' E' extend from the opposite inner ends of the frame diagonally to their point of engagement with the main levers. As it is an object to 55 condense the vertical height as greatly as

possible, these levers are arranged beneath the rods C, with only sufficient clearance to permit of the necessary movement in the operation of the scale. In this position the levers are supported by hangers F, which are in the form of loops hung over the rod C, and engaging the fulcrum pivots of the levers. The hangers F are of the twisted form shown, so that the portion of the loop which embraces the rod C extends in a plane perpendicular to the axis thereof, while the furcations of the hanger engage the fulcrum pivots of the levers. Thus when the fulcrum pivot G is engaged with the eyes of the hanger the lever will be 65 freely supported beneath the rods C, as described.

To further condense the clearance space necessary for the platform levers, the main levers are preferably in the form of a bow truss—that is, a straight beam a forms the chord of the truss, and brace members b and b' incline oppositely upward from the free ends of said beam, and are centrally connected thereto by a strut c. The shackle H 75 for coupling the short levers E' E' with the main levers is arranged above the beam a of said main lever, and has its pivot bearing upon the connecting portion of the braces b b'. These braces are preferably 80 formed of a single metal bar of oblong cross section, having the long diameter of said section arranged in a vertical plane for the opposite brace portions b b', and the bar being twisted centrally to arrange the long 85 diameter of the section horizontally. This central portion d is riveted or otherwise secured to the strut c, which is of an inverted U-shaped form, having its lower ends bolted or riveted to the beam a.

In the center of the portion d is formed the cap bearing with which the pin e of the shackle engages, said shackle having a correspondingly cupped bearing f in its lower bar for engaging the pin g of the short lever. 90 This pin g is secured to a bracket h secured to the end of the beam forming the short lever, and extending through the space between the members a and d and the U-shaped strut c. The construction just described is one which greatly economizes space, as by arranging the shackle connection above the main beam of the levers, it utilizes a space available beneath the platform. Furthermore, the lower edges of the 95 100 105 110 115 120

levers being straight they need not project beneath the plane of the lower edges of the frame sills. Thus the whole mechanism is arranged within the space of the vertical height of the sills.

The platform is supported upon the levers by bearing feet I engaging pivots J. These feet are preferably secured to longitudinal sills K K' arranged adjacent to the 10 cross bars C of the stationary frame. As shown, the sills K K' are eye-beams, and are secured to the platform by bolting planks L L' at opposite ends thereof. These planks extend beyond the sills and are spiked or 15 otherwise secured to longitudinal strips M to which the remaining planks of the platform are secured.

Instead of supporting the hangers F directly upon the rods C, I preferably extend 20 the sleeves D a sufficient distance upon the rod to form the bearings for the hangers. These sleeves have a rib or flange O on the upper side thereof, which is notched to form a retaining bearing for the hanger. Furthermore, strength is imparted to the structure 25 by providing a securing flange P upon the sleeve which is bolted to the web of the sill B, and is connected to the body portion of the sleeve by strengthening ribs Q. Thus 30 the stress of the load is transmitted directly to the sills through the medium of the member D.

What I claim as my invention is:

1. A scale comprising stationary end sills, 35 a cross rod connecting said sills, a platform lever, and a hanger for said platform lever embracing said cross rod.

2. A scale comprising stationary end sills, a cross rod connecting said sills, a platform 40 lever and a hanger for said lever engaging a pivot thereon and looped over said cross rod.

3. A scale comprising stationary end sills, a cross rod connecting said sills, a platform 45 lever extending obliquely to said sills and cross rod, and a twisted hanger engaging a pivot on said lever and looped over said rod.

4. A scale comprising stationary end sills, 50 a cross rod connecting said sills above the lower edges thereof, a lever extending beneath said cross rod bowed in the space between the same and the lower edges of said sills and a hanger for said lever looped over said cross rod.

5. A scale comprising end sills, a cross rod connecting said sills and connected platform levers operatively connected to said cross rod arranged to operate in the space beneath said rod and above the plane of the 60 lower edges of the sills.

6. A scale comprising a pair of connected platform levers, one of said levers being in the form of an upwardly bowed truss having a straight main beam and a shackle for 65 connecting said levers arranged above the main beam of said truss lever and hung from the bowed portion thereof.

7. In a scale, a platform lever comprising 70 a straight beam, a rod secured to the ends of said beam and bowed upward to form a truss therefor, a bifurcated strut connecting said rod and beam and a shackle arranged between the furcations of said strut above said beam and hung upon said rod. 75

8. In a scale, a platform lever comprising 80 a straight beam, a braced rod of oblong cross section secured to said beam arranged with the greater dimension of said section in a vertical plane and inclining upward from opposite ends of said beam, the central portion of said rod being twisted, a strut 85 connecting said central portion of the rod with said beam, and a shackle hung upon the central portion of said rod and arranged above said beam.

9. In a scale, a pair of stationary sills, a cross rod connecting said sills, a member sleeved upon said rod adjacent to said sill, a platform lever and a hanger for supporting 90 said platform lever looped over and supported by said member sleeved upon said rod.

10. In a scale, the combination with a pair 95 of stationary sills, of a cross rod connecting said sills having a threaded end passing through an aperture in the sill, a collar engaging the threaded portion of said rod on the inner side of said sill, a nut engaging said threaded portion of the rod on the outer 100 side of said sill and forming a clamp, a platform lever and a hanger for said lever looped over said rod and positioned by engagement with said collar.

In testimony whereof I affix my signature 105 in presence of two witnesses.

WALTER F. STIMPSON.
